hof, Germany, a company

Application August 3, 1932, Serial No. 627,356
In Germany August 5, 1931

10 Claims. (Cl. 250—17)

This invention relates to telegraphic valve transmitters and more particularly to the keying devices therefor, and it has for its object to keep the frequency constant.

This frequency in the case of transmitters for short or ultrashort waves largely depends upon the signaling speed. This is due to the anode plates of the valves being subjected to different degrees of temperature during the marking and spacing periods. The varying temperature causes physical distortion of the plates with the result that the inter-electrode capacity of the valves is changed. The shorter the wave length the greater is the influence of the inter-electrode capacity of the valves on the tuning of the oscillatory circuits of the transmitters, and the greater are thus the variations in frequency.

According to the invention, the thermal effect on the anode plate is equalized. To such end the continuous anode current that flows at the pauses of keying may be caused to be equal, or nearly so, to the alternating anode current which flows during a sign being given.

Other features will appear from the following description and be particularly pointed out in the appended claims, reference being had to the accompanying drawing in Fig. 1 of which one embodiment of the invention is shown diagrammatically by way of example, and in Fig. 2 of which is shown an arrangement for short-circuiting the oscillatory circuit which may be employed instead of the grounding arrangement of Fig. 1.

Referring to Fig. 1, B denotes the antenna, S the oscillatory circuit comprising inductance 5 and variable condenser 6, R the valve, W1 a resistance, W2 a second resistance, P a potentiometer, R1 a relay, R2 a second relay, V the source of biasing potential, A the source of anode potential, and T the signalling key connected with a source of current so as to control the operation of relays R1 and R2. These parts are connected in the manner that will appear from the drawing, so that relays R1 and R2 are alternately energized by manipulation of signalling key T to cause the alternate generation and non-generation of oscillations by the tube R during marking and spacing periods, respectively.

The apparatus of Fig. 1 is shown in the position of producing and sending a marking signal. In this position the left contact of key T is closed, energizing relay R2, thereby connecting resistance W1 to potentiometer P in parallel with resistance W2 to decrease the negative

polarizing potential on the grid of valve or tube R during the marking period. The connection of resistance W1 to the potentiometer P has the same effect as moving the point of connection of resistance W2 on the potentiometer P to the left would have, namely, to decrease the negative polarizing potential on the grid. While key T is thus in marking position, its right contact is open and relay R1 is de-energized so that the high frequency grounding connection for the oscillatory circuit S through resistance W3 and condenser F is open at the contact of relay R1. The valve or tube R, with its circuits, is now so connected as to produce oscillations which are impressed through the transformer onto the antenna B.

When a spacing signal is to be sent, signalling key T is manipulated so as to open its left and close its right contact. Thereupon, relay R2 releases and relay R1 energizes. The release of relay R2 disconnects resistance W1 from the potentiometer P, thereby increasing the negative polarizing potential on the grid of tube R during the spacing period. Energization of relay R1 closes its contact completing the high frequency ground connection for the oscillatory circuit S. Thereupon, the generation of oscillations ceases. However, the source of anode potential A remains connected to the anode of tube R. Therefore, unless proper provision is made, the increased flow of space current during spacing periods would cause the temperature of the tube R to be greater during spacing than during marking periods. It has been seen, however, that at the beginning of the spacing period the negative polarizing potential on the grid of tube R has been increased. This increase is sufficient to prevent the rise in space current; in other words, the resistances W1 and W2 are so proportioned with respect to the potentiometer P and source V that the total flow of current in the anode circuit during marking and spacing periods is substantially constant, whereby the temperature of the tube remains substantially constant.

In order to avoid sparking at the contact of relay R1, both relays may be so adjusted that relay R2 shall operate first so that the oscillatory circuit S is not grounded by relay R1 until the oscillations have decayed to some extent.

Stopping the generation of oscillations during spacing periods while maintaining the anode battery connected may be accomplished by short-circuiting the oscillating circuit S rather than by grounding it. Such a shortcircuiting

arrangement is shown in Fig. 2 which may be substituted, in Fig. 1, for the apparatus located within the dotted enclosure. With such substitution the operation of the sending arrangement is the same as above described in connection with Fig. 1, with the same results realized.

The grid currents that arise on the oscillations starting cause the grid to get hot so as to give rise to the same phenomena as described with respect to the anode plate. It is, therefore, advantageous also to operate by means of grid currents which are as small as possible. This is accomplished by making the resistance of W1 and W2 of the order of 10,000 ohms. The loss in output brought about thereby can be compensated by increasing the anode potential.

In an experimental arrangement, constructed as here described, during a keying pause that lasted 5 minutes and with a 13 meters wave a frequency variation of only 500 cycles occurred, that is a value not obtained hitherto in simple transmitters without the aid of artificial connections.

Changes may be made within the scope indicated by the appended claims, without departing from the idea of the invention.

What is claimed is:

1. In a telegraphic transmitter, the combination of a thermionic valve, cathode, grid and anode, a source of space current connected to the anode, an oscillatory circuit, a signalling key for producing marking and spacing signals, means controlled by the key when in marking position to so relate the oscillatory circuit with the valve as to cause the generation of oscillations, and means under control of said key for maintaining a constant thermal effect on the anode during spacing and marking periods.
2. In a telegraphic transmitter, the combination of a thermionic valve, cathode, grid and anode, a source of space current connected to the anode, an oscillatory circuit, a signalling key for producing marking and spacing signals, means controlled by the key when in marking position to so relate the oscillatory circuit with the valve as to cause the generation of oscillations, and means under control of said key for making the continuous anode current during spacing periods equal to the alternating anode current during marking periods.
3. In a telegraphic transmitter, the combination of a thermionic three-electrode valve, cathode, grid and anode, a source of space current connected to the anode, an oscillatory circuit, a signalling key for producing marking and spacing signals, means controlled by the key when in marking position to so relate the oscillatory circuit with the valve as to cause the generation of oscillations, and means under control of said key for so altering the grid potential thereof as to make the continuous anode current during spacing periods equal to the alternating anode current during marking periods.
4. In a telegraphic transmitter, the combination of a thermionic three-electrode valve having cathode, grid and anode, a source of space current connected to said anode, an oscillatory circuit coupled to said valve, a signalling key for producing marking and spacing signals, means for short-circuiting such oscillatory circuit during spacing periods, and means for increasing the negative grid polarizing potential applied to the grid during spacing periods, both these means being operable conjointly under control of said key.

5. In a telegraphic transmitter, the combination of a thermionic three-electrode valve having cathode, grid and anode, a source of space current connected to said anode, a source of polarizing potential connected to said grid, an oscillatory circuit coupled to said valve, means for earthing such oscillatory circuit during spacing periods, and means for increasing the negative polarizing potential applied to said grid during spacing periods, both these means being operable conjointly under control of said key. 5

6. In a telegraph transmitter, the combination of a thermionic tube having cathode, grid and anode, a source of space current connected to the anode, an oscillatory circuit, a signalling key for providing marking and spacing signals, means for applying a polarizing potential to said grid, means controlled by said key for causing an effective connection of said oscillatory circuit to said tube during marking periods whereby during said periods oscillations are generated, and means controlled by said key during spacing intervals for causing said tube to cease generation of oscillations and for so altering the polarizing potential applied to said grid that the anode current during spacing periods is maintained at substantially the same value as during marking periods. 20

7. In a telegraphic transmitter, the combination of a thermionic tube having cathode, grid and anode electrodes, a source of space current connected to the anode, an oscillatory circuit, means for connecting said circuit to the electrodes of said tube whereby oscillations are generated, a signalling key for providing spacing and marking signals, means controlled by said key for causing the tube to generate oscillations during marking periods, and means responsive to manipulation of the key from marking to spacing position to establish a path from said cathode to said grid external to said tube thereby causing said tube to cease generation of oscillations whilst maintaining said space current source connected to said anode. 30

8. In a telegraphic transmitter, the combination of a thermionic tube having a grounded cathode, a grid and an anode, a source of space current connected to the anode, an oscillatory circuit, means for connecting said circuit to the cathode, grid and anode of said tube whereby oscillations are generated, a signalling key for providing spacing and marking signals, means controlled by said key for causing the tube to generate oscillations during marking periods, and means responsive to manipulation of the key from marking to spacing position to establish a path from said oscillatory circuit to ground whereby generation of oscillations ceases whilst maintaining said space current source connected to said anode. 45 50

9. In a telegraphic transmitter, the combination of a thermionic tube having cathode, grid and anode, a source of space current connected to the anode, an oscillatory circuit, means for connecting said circuit to the cathode, grid and anode of said tube whereby oscillations are generated, a signalling key for providing spacing and marking signals, means controlled by said key for causing the tube to generate oscillations during marking periods, and means responsive to the manipulation of the key from marking to spacing position to shortcircuit said oscillatory circuit, thereby to cause a cessation of the generation of oscillations during spacing periods 70 75

whilst maintaining said space current source connected to said anode.

10. In a telegraphic transmitter, the combination of a thermionic tube having cathode, grid and anode, a source of space current connected to the anode, means for negatively polarizing said grid, an oscillatory circuit, means for connecting said circuit to the cathode, grid and anode of said tube whereby oscillations are generated, a signalling key for providing spacing and marking signals, means controlled by said

key for causing the tube to generate oscillations during marking periods, and means responsive to manipulation of the key from marking to spacing position to cause the tube to cease generation of oscillations and for so increasing negatively the polarization potential applied to said grid that the anode current during spacing periods is maintained at substantially the same value as during marking periods. 5
